UNITED STATES PATENT OFFICE.

GEORGE GLASS, OF MILWAUKEE, WISCONSIN.

CONVEYER.

1,426,179.

Specification of Letters Patent. Patented Aug. 15, 1922.

Application filed March 1, 1919. Serial No. 279,956.

To all whom it may concern:

Be it known that I, GEORGE GLASS, a citizen of the United States, residing at Milwaukee, in the county of Milwaukee and 5 State of Wisconsin, have invented new and useful Improvements in Conveyers, of which the following is a full, clear, concise, and exact description, reference being had to the accompanying drawing, forming a part of 10 this specification.

My invention relates to improvements in conveyers, and, more particularly, to endless conveyers of the type used in pea-cleaning machines, wherein there is provided a conveyer consisting of a substantially continuous series of buckets or troughs extending over the floor of a liquid-filled container.

One of the objects of my invention is to provide a bucket conveyer of the above type 20 which shall be free from crevices in which the peas can lodge, and which at the same time shall be so constructed as to turn over a small sprocket.

Another object of my invention is to provide a conveyer of the above type which will be perfectly smooth during the passage 25 through the container, and which will have no projections or separating parts between which the peas can be caught and crushed. 30 For the purpose of disclosing my invention I have illustrated one embodiment thereof in the accompanying drawings, in which—

Fig. 1 is a side elevation of a separating 35 machine having my improved conveyer;

Fig. 2 is a sectional view taken on the line 2—2 of Fig. 1;

Fig. 3 is a detail plan view of my improved conveyer;

40 Fig. 4 is a sectional view thereof taken on the line 4—4 of Fig. 3;

Fig. 5 is a sectional view taken on the line 5—5 of Fig. 3; and

Fig. 6 is an elevation showing the manner 45 of passing the conveyer over a small sprocket.

Referring to the drawings, the container 2, having an arcuate bottom and being comparatively narrow with respect to its length, 50 is mounted on suitable supporting legs 3. At each end of the conveyer on suitable supporting frames are journaled two shafts 5, each having a pair of spaced-apart sprockets 6 mounted thereon. One of the shafts 5 is 55 additionally provided with a driving sprocket 7 over which passes the driving

chain 8. The endless conveyer 9 passes over these two sets of sprockets and is arranged in its receiving position to pass within the container along the arcuate bottom thereof. 60 This conveyer, as shown in Figs. 3 to 5, is composed of a plurality of links, each link forming a bucket, downwardly tapering or substantially triangular-shaped in cross section, with the bottom portion inclined rearwardly with respect to the plane of the mouth of the bucket. The two sides 10 of this bucket are preferably formed of cast iron and have inwardly-extending flanges 11 from which project rivet-receiving lugs 70 12. The upper edges of these side members have reinforcing side flanges 13 and at the rear of the side members are formed openings through which the connecting bolts 14 are adapted to pass. Extending forwardly 75 from the side members and formed integrally therewith are extensions 15. These extensions, in effect, are continuations of the top flanges 13 and have downwardly-extending side portions 16, the distance, however, between these side portions being greater than the distance between the sides 80 of the buckets. These side portions 15 are likewise provided with openings through which the securing bolts 14 pass. In connecting the buckets together by the bolts it will be seen that the extensions 16 are spaced far enough apart to fit on the outside of the rear portion of the next succeeding bucket. The bottom and front and rear walls of each 90 bucket are formed of a single piece of sheet metal 17 secured to the flanges 11 by rivets passing through this metal and through the lugs 12. The upper edge of the rear wall is rolled over to form a beaded lip 18, through 95 which the bolt 14 passes. To span the spaces between the buckets, the front wall of each is provided with a plate extension or lip 19 which overlaps the rear wall of the next preceding bucket said lip being curved 100 downwardly and fitting over the bead 18 to form a close-fitting joint at this point. It will be noted that, due to this construction, when the buckets move relatively to one another this curved lip 19 fits nicely onto the 105 bead 18 and there are no crevices or openings formed into which the peas can be crowded and crushed. Secured on each end of the bolts 14 which connect the links together are rollers 20 which provide support- 110 ing means for the buckets.

The piece of sheet metal 17, as shown in

Fig. 4, is shaped to form a rear wall 20^a for the buckets, a bottom portion 20^b, a front wall portion 20^c, and a bridging portion 20^d. The front wall 20^c of the bucket forms an acute angle with respect to the mouth 20^e of the bucket, while the rear wall 20^a, forms an obtuse angle with respect to the mouth 20^e. Since the single piece of sheet metal 17 is secured to the flanges 11 and legs 12 by rivets, as previously described, the front and rear walls of the bucket are rigid with respect to each other.

As will be seen in Fig. 6, the sprockets 6 are provided with suitable notches 21 into which these rollers fit, so that the conveyer will readily pass around this sprocket, and, due to the fact that the extensions 16 are sufficiently spaced apart so that the sides of the adjoining bucket will fit between the same, the conveyer can turn on a very short arc. This turning of the conveyer on a short arc is rendered possible by reason, also, of the spacing between adjacent buckets and the downwardly tapering rounded formation thereof, which permits each bucket, notwithstanding the rearward inclination thereof, to assume a position in which the bottom portion thereof overlaps and is disposed in close proximity to the mouth portion of the next succeeding bucket, and in which one end of each bucket is disposed substantially parallel with the plane of the mouth of the succeeding bucket.

As shown in Fig. 2, the buckets lie substantially within the circumferential confines of the sprockets as they travel over said sprockets, and the teeth of the sprockets have a pitch equal to the distance between the connections of the buckets. Also as shown in Fig. 6, the rear wall and bottom of the buckets form a sort of heel portion which fits into and is embraced by the bridging portion and front wall of the succeeding bucket as the buckets pass around the sprockets.

At the bottom of the container and secured to each side thereof are provided channel-irons 22 beneath which the rollers 20 pass and which serve as guides to maintain the travel of the conveyer along the bottom of the container. Also arranged in the container on each side thereof are deflectors 23 which are inclined to such a position that the distance between the same is just equal to or slightly less than the width of the

conveyer buckets, whereby the peas will be guided into the buckets and there will be no danger of their dropping on either side of the buckets between the conveyer and the container.

While I have illustrated and described one embodiment of my invention in the accompanying drawings and specification, it will be understood that my invention may take other embodiments and changes may be made in the one illustrated and described without departing from the spirit thereof as set forth in the appended claim.

I claim as new and desire to secure by Letters Patent of the United States:

A conveyer construction comprising a series of bucket members connected together to form an inclined run, sprockets at the upper end of said run around which said buckets pass, each bucket member comprising a pocket portion and a bridging portion, said buckets lying substantially within the circumferential confines of the sprockets as they travel over said sprockets, said pocket portion being open on top to form a mouth lying substantially in a plane extending longitudinally of the plane of travel of the bucket, and comprising front, rear and side walls, said front, rear and side walls being rigid with respect to each other, said pocket being suspended in substantially vertical position on said inclined run, said bridging portion bridging the space between adjacent pockets and lying substantially in the plane of the mouth of its pocket, the front wall of the pocket forming an acute angle with respect to the mouth, and the rear wall of said pocket forming an obtuse angle with respect to the mouth, the rear wall and bottom of the bucket forming a heel portion which fits into and is embraced by the bridging portion and front wall of the succeeding bucket as the buckets pass around the sprockets, the teeth of said sprockets having a pitch equal to the distance between the pivotal connections between the buckets, and having operative engagement with the buckets at the pivotal points, the pivotal connection between the buckets being at the point of connection between the bridging portion of one bucket and the adjacent rear wall of the preceding bucket.

In witness whereof, I have hereunto subscribed my name.

GEORGE GLASS.
